UNITED STATES PATENT OFFICE.

JOSEPH A. McLANE, OF WASHINGTON, DISTRICT OF COLUMBIA, ASSIGNOR, BY MESNE ASSIGNMENTS, TO PEOPLES NATURAL GAS COMPANY, A CORPORATION OF PENNSYLVANIA.

BURNER FOR HEATING FURNACES.

Application filed March 31, 1927. Serial No. 179,883.

It is the object of the invention to provide a burner for liquid and gaseous fuels, or either as desired, which, while not limited to any specific purpose for which it is suitable, 5 is particularly adapted for domestic use, in heating furnaces in residences and other buildings. And stated more specifically the object is to provide a burner of the type indicated, which will be of small bodily 10 pass, of the economical and simple construction which is desirable, will permit only a minimum, if any, accumulation of deposit from the products of combustion while at the same time it may be easily cleaned, and 15 will be of high efficiency.

In the accompanying drawings, wherein is shown only one embodiment of the invention in the form now considered to be the best, Figure 1 shows, conventionally only, a 20 cross-sectional elevation of a furnace of a domestic hot-water heating system of a common type, with the burner shown in rear elevation. Figure 2 is a plan view of the burner. Figure 3 is a view on a larger scale of 25 the burner in medial longitudinal section. Figure 4 is a view in perspective of the hood. Figure 5 is a detail. Figure 6 is a view in elevation of the vaporizer.

Figure 1 shows the burner installed in a 30 domestic furnace originally intended for use with other fuel, in which 1 is the furnace chamber overarched by a water-chamber 2, and having grate-bars 3, with the usual chimney (not shown). The grate-bars are covered by a plate 4 having a suitable orifice to receive the depending portion of the burner. The body of the burner has a depending bowl 5 having a drip outlet 6, and front and side flanges 7 which are supported by the edges 35 of the plate 4 surrounding the orifice. Above these flanges there are opposite side walls 8 and a rear wall 9 terminating in a substantially semi-circular overhang 10 extending across the structure at the top, and spaced beneath which is the forwardly-projecting and 40 downwardly-curved shelf 11, which also extends across the structure, and which together with the overhang 10 and the opposite extensions 8^a of the side walls 8, 8, forms 45 a transverse chamber 51 having a transverse front outlet 12. Extending nearly from end to end of the chamber 51 is a header 13 for the liquid fuel, preferably oil, which is shown as a piece of tubing closed at its opposite ends 50 and is provided with nozzles 14 at intervals,

which nozzles are preferably inclined somewhat upwardly as shown. The numeral 15 indicates the oil-supply pipe which is connected to the center of the header 13. This header 13 with its nozzles 14 constitutes an 60 oil-burner.

Below the forwardly-projecting and overhanging shelf 11 is the transverse header 16, which is connected at one end to the gas-pipe 17, and which has a transversely arranged 65 series of forwardly directed nozzles 18. This structure acts as a gas burner when the gas is turned on.

Air is supplied to the burner through a broad transverse passage 20 at the rear, and between the rear wall 9 above mentioned and the corresponding rear wall 19 of the removable hood 21, which has opposite side walls 23 which fit over the opposite side-walls 8 above mentioned, and a dome-shaped forwardly-projecting roof 24. The opposite side-walls 23 of the hood are provided with slots 25 to receive the connecting pipes hereinabove and hereinafter described. The rear wall 19 of the hood and its roof 24 are 70 so conformed in shape to, and so spaced from, the rear wall 9 and arched overhang 10 of the burner as to afford a free and unconstricted passageway for the entering air, and the forwardly-projecting portion of the roof 24, 75 curving down to its terminus 50, is so shaped as to define a still more greatly enlarged combustion chamber in advance of the oil burner and of the gas burner, so as to afford maximum efficiency of combustion. The outer 80 transverse lip 50 of the hood may, as shown, and should, stand above the level of the floor 4 of the structure for a slightly greater distance than does the tip of the overhanging shelf 11. The hood 21 has an eye or handle 85 95 attached to it, so that it may be readily removed and replaced.

At a point forwardly of the two burners and rearwardly of the tip 50 of the hood there is provided a transversely extending hearth-piece 27, the rear end of which is substantially beneath the tip of the overhanging shelf 11 and is sufficiently spaced therefrom to afford a clear outlet across the burner in the line of the nozzles 18. This hearth-member 27 is 100 slightly trough-shaped, as shown, and may be provided with a mat of asbestos or equivalent liquid-absorbent material.

Spaced forwardly from the broad transversely extending outlet between the tip 50 of 110

the hood and the floor 4 of the structure there is arranged transversely a hollow vaporizer 29, supported on opposite legs 30 which rest on the floor 4. At one end the vaporizer 29 is provided with an inlet for water supply from the pipe 31, and at the opposite end with a steam delivery pipe 52 which is connected to the header 16 at the end opposite to its gas-pipe connection 17. At or near the opposite ends of the header 16 there are upwardly-projecting pipes 32 which are adapted to deliver jets of steam into the opposite ends of the transverse chamber 51, which contains the oil-burner. These pipes 32 are so arranged and punctured as to deliver the steam into the chamber 51 not only in the space above the oil-burner but into whatever space there may be between the oil-burner and the shelf 11 immediately beneath it. The punctures or jet openings in the pipes 32 are indicated so far as possible by the numeral 33. These jets not only serve to keep the chamber 51 and the surface of the shelf 11 free from deposits of carbonaceous matter, but they have a spraying effect upon the slightly upwardly directed jets of oil, and the oil is driven in a spray so as to be effectively intermingled with the air in the combustion chamber.

Understanding that the oil-supply pipe, the gas-supply pipe and the water-supply pipe are all provided with suitable regulating valves accessible outside the furnace structure, the operation will be obvious. Original ignition is accomplished by turning on the gas, and lighting it and then turning on the oil. Under natural draft a high heat is soon generated, the gas is turned off and the water commences to vaporize freely in the vaporizer 29, thus supplying steam to the header 16, from which it issues directly through the nozzles 18 into the combustion chamber, and supplying steam as well through the pipes 32 and the punctures 33 into the space above and below the oil-burner, the steam acting to prevent or eliminate any deposits of solid carbonaceous matter from the products of combustion, and effecting the utilization of all of the fuel in the most efficient manner.

In an embodiment of the invention which I have installed, oil is supplied to burner 13 under a head of 10 inches; the openings 14 are one eighth of an inch in diameter. When conditions of continuous operation have been established, the oil is supplied at a rate of one gallon an hour, and from the openings 14 jets of oil spurt and impinge upon the inner surface of overhang 10. The jets of steam through openings 33, impinging upon the spray of oil which rebounds from overhang 10 and fills chamber 51, tend further to subdivide the oil and, preventing deposit on the chamber walls, form with the oil a more highly combustible gaseous mixture, hot, and under pressure. This mixture rushes from the outlet 12 and, meeting the stream of air, breaks into

rapid and complete combustion, so that an intensely hot flame is delivered from beneath lip 50.

The character of the air-admission conduit at the top of the combustion chamber which is defined by the roof 24 of the hood 21, largely contributes to this efficiency in operation. The air has a free and unconstricted passage into the combustion chamber, and the combustion chamber itself is so formed as to provide free intermingling of air and fuel.

In case gas should be used as a fuel instead of oil, the oil supply and the water supply of course will both be shut off, and combustion will be obtained with gas and air only. But in this case also the form of the air-supply conduit and the form of the combustion chamber both provide for maximum efficiency.

In the furnace illustrated in Figure 1 the flame advantageously plays upon a body 34 of refractory material which is a heap of fire brick set within the furnace and near the furnace opening.

It will be understood that the foregoing is intended to describe only the preferred embodiment of the invention, and that the invention itself is not otherwise limited in its scope than by the terms of the appended claims.

I claim as my invention:

1. A burner for heating-furnaces comprising in combination a combustion chamber having an air-inlet, a supplemental chamber opening into the combustion chamber, an oil-header having discharge outlets located in the supplemental chamber, a second header having discharge outlets to the combustion chamber, a vaporizing chamber exposed to the heated products of the combustion chamber, and means for supplying steam from the vaporizer to said supplemental chamber and to said second header.

2. A burner for heating-furnaces comprising in combination a transverse chamber having a back wall an outwardly inclined floor and a curved overhanging roof the lower edge of which forms with said floor a transverse outlet from said chamber, an elongated fuel burner located in said chamber, and a removable hood so shaped as to form with the back wall and roof of said chamber an unconstricted air port and having an overhanging roof developed on a greater radius to provide an expanded combustion-chamber in front of said outlet.

3. A burner for heating-furnaces comprising in combination a chamber having a back wall a floor and a curved overhanging roof, the lower edge of which forms with said floor a transverse outlet from the said chamber, means for causing a jet of oil to impinge transversely within said chamber upon said overhanging roof, means for injecting a jet of steam longitudinally within said chamber, and an air passageway overarched said

chamber, into which said transverse outlet opens.

4. A burner for heating-furnaces comprising in combination a transverse chamber having a back wall a floor and a curved overhanging roof, the lower edge of which forms with said floor a transverse outlet from said chamber, the said transverse chamber being arranged within another chamber having a 10 back wall a floor and a curved overhanging roof, whose lower edge forms with the floor a transverse outlet from such outer chamber, means for causing a jet of oil to impinge upon the overhanging roof of the chamber first 15 named, means for injecting a jet of steam within the chamber first named, the walls and roofs of the two said chambers constituting together the opposite walls of an air passageway leading from the rear, over the roof of 20 the inner chamber and to the orifice from the outer chamber, the orifice from the chamber first named opening to such air passageway.

5. A burner for heating-furnaces comprising in combination two superposed transverse chambers having each a back wall and 25 an overhanging roof the lower edge of which forms the upper edge of a transverse outlet from the chamber, two headers provided with nozzles, one of which extends transversely within each of said chambers, an oil supply 30 pipe leading to the header in the upper chamber, a gas supply pipe leading to the header in the lower chamber, a steam supply pipe leading to the header in the lower chamber, means for conveying from the header in the 35 lower chamber and for projecting in a jet within the upper chamber a stream of steam, and an air passageway overarching said superposed chambers and to which the outlets of the two said chambers open. 40

In testimony whereof I have hereunto set my hand.

JOSEPH A. McLANE.
